ATTACHMENT FOR CRANES

John J. Gault, Chicago, Ill., assignor to William J. Newman Company, Chicago, Ill.

Application March 2, 1931. Serial No. 519,606

1 Claim. (Cl. 212—65)

This invention relates to attachments adapted for use with cranes and particularly standard cranes having the usual booms, to provide means for handling various materials and particularly for handling concrete on high and wide lifts. If the boom of a standard crane is lowered to give sufficient horizontal distance or swing it is frequently impossible to project the end of the boom over a wall or the like so as 10 to place material at a substantial distance from the crane and at a relatively high elevation. The present invention is intended to overcome these limitations of a standard crane by providing an attachment which may be readily applied thereon 15 to and which will serve to perform work or operations not possible with the ordinary crane. The objects of the invention are to provide a cantilever boom or extension for a standard crane boom; to provide means whereby a standard crane may be utilized for placing material at greater heights and distances from the body 20 of the crane than is possible with the crane boom; to provide an attachment of the character indicated which may be applied to and removed 25 from a standard crane with but little inconvenience or changes in the crane; to provide a crane with novel material handling mechanism; and to provide such other advantages and features of construction as will appear from the 30 following description taken in connection with the accompanying drawings in which;

Figure 1 is a side elevation illustrating a crane of the caterpillar type with one form of my attachment applied thereto;

35 Figure 2 is an end view;

Figure 3 is a plan view of a cantilever or extension boom;

Figure 4 is a sectional detail taken on the line 4—4 of Figure 1;

40 Figure 5 is a sectional detail taken on the line 5—5 of Figure 1;

Figure 6 is a side view showing a modified form of construction and indicating the purposes of the attachment;

45 Figure 7 is a plan view of a portion of Figure 6; and

Figure 8 is a sectional detail taken on the line 8—8 of Figure 7.

In all of these figures parts are shown diagrammatically for convenience in illustration.

As shown in Figure 1, 10 indicates a standard crane having a body or main frame 11 rotatably mounted on endless belt tractors 12 of the caterpillar type. The crane has a boom 13 with a 55 shaft 14 at the outer end for supporting the

guide sheave or sheaves 15. This shaft is preferably elongated to provide a support for a cantilever boom or transverse beam 16. This boom may be made in any suitable manner but is shown as constructed with side beams or 60 channels 17 and suitable cross bracing to form a stiff and substantial boom. The side beams 17 have sections of angles 18 secured thereto to embrace the ends of the shaft 14 thereby forming bearings for the boom so that the boom may 65 be readily placed in position or removed from the shaft. An anchor frame or post 19 is connected with the rear end of the boom 16 by a cross bolt or shaft 20 and extends down to the frame 11 to which it is attached by means of a 70 suitable A-frame 21. The anchor frame 19 is preferably built up of side beams 22 and suitable cross bracing 23 to make a rigid structure.

A sheave 24 is mounted at the outer end of the boom 16 and the hoist line or cable 25 from 75 the drum 26 passes over it as well as the sheave 15. The free end of the cable may be provided with a hook 27 or other suitable means for lifting loads such as buckets or containers for concrete.

The operation of this crane will be readily understood but attention is called to the fact that with this novel construction, the material may be picked up off from the ground and then swung out and elevated to a higher position than would 85 be possible with the standard crane boom.

Figures 6 to 8 show a modified form of construction as also applied to a standard crane. In this form the cantilever boom 28 comprises a rear frame portion 29 which is supported on the 90 shaft 14 as heretofore described and is connected at its rear end with the body of the crane by an anchor frame 30. At the outer end of the boom 28 is an eye beam or other suitable beam 31 to provide a track for a carrier 32 of the type 95 commonly known as a hay carrier.

The crane is provided with one drum 33 having a cable or line 34 which passes over a sheave 35 on the crane boom 13, then over a sheave 36 at the end of the boom 28 and back to the carrier or carriage 32. This line from the drag drum serves to move the carriage out to any desired position along the boom and the boom may be inclined so that the carriage will run back to loading position by gravity.

A hoist cable 37 leads from a second drum 38 on the crane over a guide sheave 39 at the end of the boom 13 then over a pulley 40 on the carriage 32, then down under a pulley 41 which supports a lifting hoist 42 and its outer end is con- 110

nected at 43 to the carriage 32. The beam 31 is provided with adjustable trips 44 and 45 for releasing the hook. As the construction of such carriages is well known and forms no part of this invention, further description will be omitted. Any suitable bucket or receptacle 46 is carried by the hook 42 for receiving the material to be elevated.

Figure 6 indicates the method of operation of the device in placing concrete or the like on the top of an elevated structure such as shown at 47. When the carriage is at an inner position as shown in full lines in this figure, the cable 37 may be slackened which permits the bucket 46 to descend to the ground preparatory for filling. As soon as the bucket is filled the cable 37 is wound up thereby elevating the bucket until the catch on the carrier 32 trips or engages so as to hold the pulley 41 and hook suspended from the carriage. The cable 37 is then payed out and the cable 34 is wound up, thereby pulling the carriage 32 out along the beam or track 31 until it engages with the trip 45 which releases the pulley and hook thereby permitting the bucket 46 to be lowered to dumping position over the structure 47. After it is dumped the reverse operations take place preparatory for again filling the bucket.

By means of this arrangement a standard crane may be utilized to elevate and place the material much more rapidly and efficiently than when used in the ordinary manner. With this particular form the material may be handled

without rotating the crane as well as obviating the necessity of raising and lowering the crane boom.

Furthermore, with either form of the invention, material may be elevated and deposited in positions which would be impossible or inconvenient to reach with an ordinary crane. It will of course, be understood that sufficient counter-weight is provided to balance the structure and the load as is common with machines of this character. It will also be noted that the details of construction may be varied in order to adapt the attachment for different uses or for different makes of cranes and therefore I do not wish to be limited to the constructions shown and described except as specified in the following claim, in which I claim.

The combination with a standard crane having a rotatable main frame and swinging boom carried thereby, of an elongated shaft at the outer end of the boom for supporting a sheave, a cantilever beam having open bearings adapted to rest on the shaft for detachably supporting the beam, a post secured to the main frame and projecting upwardly with its upper end connected with the inner end of the beam, and a sheave mounted at the outer end of the beam, the arrangement being such that the beam provides an extension for the boom whereby the effective height and radius for carrying loads is substantially increased.

JOHN J. GAULT.
